[57] CLAIM

A design for a wire brush for attachment to a power tool, as shown and described.

DESCRIPTION

FIG. 1 is a side elevational view of a wire brush for attachment to a power tool showing my new design; FIG. 2 is a right end elevational view thereof; FIG. 3 is a side elevational view thereof, rotated approximately 90 degrees; FIG. 4 is a left end elevational view thereof; and FIG. 5 is a cross sectional view taken along line 5—5 of FIG. 1.

The undisclosed sides are the same in appearance as the sides shown.

FIG. 1

FIG. 2

FIG. 3

FIG. 4

FIG. 5

UNITED STATES PATENT AND TRADEMARK OFFICE
CERTIFICATE OF CORRECTION

PATENT NO. : Des. 308,623
DATED : June 19, 1990
INVENTOR(S) : Nobuo NISHIKI

It is certified that error appears in the above-identified patent and that said Letters Patent is hereby corrected as shown below:

On the title page: Item [75]

--No. 406, Sanko Dai-Roku Heights
15-7, Izuo 4-chome, Taisho-ku, Osaka-shi
Osaka-fu, JAPAN--

Signed and Sealed this
Third Day of May, 1994
